UNITED STATES PATENT OFFICE

2,170,105

DISPENSER

Walter E. Amberg, Chicago, Ill., assignor to Universal Paper Products Company, Chicago, Ill., a corporation of Illinois

Application January 25, 1937, Serial No. 122,185

3 Claims. (Cl. 312—43)

This invention relates to dispensing devices and more particularly to a device designed to dispense cone-shaped paper containers, such, for example, as drinking cups, sundae dishes and the like. An object of the invention is to provide a dispensing device of the aforementioned character which is simple in design and construction, economical in manufacture and efficient in operation.

With these desiderata in view, a feature of the invention resides in constructing a dispenser consisting of only two parts, each of which is of plain, uncomplicated design. As so constructed the dispenser is entirely free of moving parts, thereby further increasing the simplicity and economy of design.

One of the two parts of the dispenser comprises merely a dome-shaped member having positioning slots in its lower extremity, whereas the other part is a base member having a cup-emerging area and a plurality of positioning members extending upwardly therefrom for engagement within the slots formed in the lower extremity of the dome. Thus, it will be seen that the objects of economy and simplicity have been carried out.

A feature of the invention which contributes largely to the efficient operation of the dispenser resides in the arrangement or shape of the cup-emerging area. To prevent the accidental removal of more than one cup at a time and to support the cups properly within the dispenser, the base is provided with a circular opening at its upper portion which tapers into a regular polygonal passageway at its lower portion. A cup-emerging area of this configuration permits cone-shaped cups to be removed with the slightest amount of deformation, yet a sufficient amount to permit such removal to take place without substantial resistance.

Other objects and features of the invention will become apparent from a reading of the following specification in the light of the accompanying drawing, in which

Figure 1 is a view in front elevation of a dispenser constructed in accordance with the present invention;

Figure 2 is a view in side elevation having a portion thereof broken away, of the dispenser illustrated in Figure 1;

Figure 3 is a sectional view taken along the line 3—3 of Figure 2; and

Figure 4 is a bottom plan view of the dispenser shown in the earlier figures.

As previously stated, simplicity in design and economy in manufacture are important objects of

the instant dispenser. Thus, as illustrated, the dispenser comprises a base 10 and a dome or magazine 12. The base, which may be of a single piece casting, includes a tongue member 14 suitable for engagement with the customary wall bracket groove and a plurality of vertically extending, supporting columns or guides 16 extending upwardly therefrom. As illustrated in the cut-away portion of Figure 2, and more particularly in Figure 3, the inner edges of the supporting columns 16 are flared outwardly to provide flange portions 18 adapted to engage, by means of slots 20 formed in the bottom extremity of the dome or magazine 12, the inner walls of said dome. The inner edges of the columns 16 are so spaced as to have supporting engagement with a stack of cups nested within. Thus, in disassembling the dispenser to permit the insertion of additional cups or containers, the dome 12 may be grasped and lifted upwardly to be removed entirely from the base member 10. After the cups are deposited within the base, the dome may again be placed in position by bringing the slots formed in the base into registry with the positioning columns or posts 16. When this has been accomplished the dome is then free to move downwardly into a position in which its lower edge 22, which is slightly flared out to afford a better seal, engages the upper circular rim of the base member 10.

Also, as previously pointed out, a feature of the invention resides in the provision of a cup-emerging area or passageway which will efficiently support the cups under normal conditions and will permit removal of the lower one without accidental displacement of any others, and with a minimum amount of distortion being imparted to the cup so removed.

As shown in Figures 2 and 3, the upper rim, edge or opening 24 of the base member 10 is circular in cross section. However, the side walls of the base member as they extend downwardly from the upper edge gradually change in cross sectional shape until upon reaching the lowermost edge 26 the circle has disappeared and a regular polygonal or triangular opening has taken its place. The triangular mouth is well illustrated in the bottom plan view of Figure 4 in which the sides of the triangle are indicated by the reference numerals 28, 30 and 32. When a stack of cups is normally positioned within the dispenser, the lowermost cup is engaged by the inwardly sloping walls of the cup dispensing areaway over a substantial space. The extent of the surface of the cup that is engaged by the ring or base 10 is indi-

cated by the fact that where the walls of such base slope inwardly and downwardly, the slope corresponds substantially to the contour or shape of the cup, and thus the stack is supported by engagement with the lowermost cup along three uniformly spaced areas which are located at the central portions of the downwardly and inwardly sloping triangular side walls. It will be appreciated also, as seen from Figures 3 and 4, that the 10 wall of the base member 10, in addition to the downwardly and inwardly sloping sides, comprises downwardly and outwardly extending portions which form the apexes of the triangular shaped opening. Upon the lowermost cup, illustrated by the dotted lines A in Figures 1 and 2, being grasped by the fingers of a user, the downwardly exerted pressure causes the cup to detach itself from the stack and move downwardly through the cup-emerging area. As this movement takes place the mouth of the cup is changed to conform to the configuration of the side walls and as the triangular shape is assumed the separated cup reaches the lower edge of the passageway. Accidental displacement of more than 15 one cup at a time is efficiently and firmly prevented by means of the sloping side walls of the base member 10. As pressure is exerted to remove the lowermost cup the containers directly thereabove have firm frictional engagement with the sloping side walls of the base over an area of substantial width or depth which assures satisfactory operation. For example, if two cups should start moving when a user intends to remove the lowermost only, the second, by virtue 20 of its continual and prolonged engagement with the sloping side walls of the base, would eventually come to rest, permitting the removal of only the cup intended. In order to demonstrate the efficiency of the retaining ring or base 10 in 25 supporting a stack of cups, it may be pointed out that the only way to move a stack of cups through the discharge opening is by removing them from the bottom of the stack. Pressure applied to the top of the stack merely results in 30 more firmly seating the cups upon the inwardly sloping portions of the base, thereby causing these portions to act as a shelf and to resist any downward movement.

Although the mouth of the cup-emerging area 35 has been disclosed herein as of triangular shape, it must be appreciated that it may assume other suitable regular, i. e., having sides of equal length, polygonal shapes.

By means of regular polygonal openings the

cups are firmly supported and the pressure during removal is applied at a plurality of points, the number of which corresponds to the number of sides.

It will be understood that various changes in design and construction and rearrangement of parts may be effected without constituting a departure from the invention as outlined herein and set forth in the appended claims.

Having thus described the invention, what I claim as new and desire to secure by Letters Patent of the United States is:

1. A dispensing device for paper cups having converging side walls, said device having an emerging area with alternately arranged portions sloping downwardly and inwardly in general conformity to the converging side walls of the cups and adapted to support a stack of cups, and other portions of said emerging area sloping downwardly and outwardly and adapted to permit the withdrawal of a cup from the bottom of the stack.

2. A dispenser for paper cups having converging side walls and a circular mouth, said dispenser having lateral cup-retaining means adapted to hold a stack of nested cups in substantially upright position, cup-supporting means integrally associated with the lateral cup-retaining means and including sides of a polygon forming an exit for withdrawal of cups from the bottom of the stack one at a time, said cup-supporting means having downwardly and inwardly sloping portions conforming generally to the angle of slope of the walls of the cups and said polygon having corner portions into which the bottom cup of the stack recedes gradually without creasing as it is withdrawn.

3. A dispensing device for paper cups having converging side walls, said device having a circular emerging area which gradually changes to a polygonal exit with at least three sides as it progresses in a downward direction and which tapers inwardly at alternately arranged portions in general conformity to the slope of the converging side walls of the cup, said inwardly tapered portions terminating in the sides of the polygon at the exit and being adapted to support a stack of cups, and said dispenser having non-supporting portions between said downwardly and inwardly tapering portions into which the bottom cup of the stack is adapted to recede gradually without creasing as it is withdrawn through the cup exit.
